UNITED STATES PATENT OFFICE

133,539

DESIGN FOR A RADIO CABINET

Henry J. Dow, Minneapolis, Minn.

Application April 24, 1941, Serial No. 100,604

Term of patent 14 years

To all whom it may concern:

Be it known that I, Henry J. Dow, a citizen of the United States, residing at 1736 James Avenue South, city of Minneapolis, in the county of Hennepin and State of Minnesota, have invented a new, original, and ornamental Design for a Radio Cabinet, of which the following is a specification, reference being had to the accompanying drawings, forming part thereof, and in which

Figure 1 is a side perspective view of a radio cabinet showing my new design;

Figure 2 is a front perspective view;
Figure 3 is a top plan view; and
Figure 4 is a rear perspective view.

The characteristic feature of my design resides in the radio cabinet illustrated in combination with the circular speakers in the specific arrangement all as shown.

I claim:

The ornamental design for a radio cabinet, substantially as shown and described.

HENRY J. DOW.
